his Attorney

UNITED STATES PATENT OFFICE.

SHELTON J. GUNN, OF GUNNTOWN, FLORIDA.

IRON-BOUND BOX COVER.

Application filed October 13, 1921. Serial No. 507,516.

To all whom it may concern:

Be it known that I, SHELTON J. GUNN, a resident of Gunntown, in the county of Levy and State of Florida, a citizen of the 5 United States, have invented certain new and useful Improvements in Iron-Bound Box Covers, of which the following is a specification.

My invention relates to an improvement 10 in iron-bound box cover.

The object is to provide a metal binder for the ends of wooden box covers, which will be securely attached thereto throughout the width of the ends, with the ends of 15 the metal protruding sufficiently to form means whereby they are capable of being bent down and secured to the box.

The iron-bound box covers are particularly adapted for orange-boxes, although it 20 is understood their application might be greatly extended, according to requirements.

In the accompanying drawings:

Fig. 1 is a top view;

Fig. 2 is a bottom view;

25 Fig. 3 is a section on line 2—2 of Fig. 2;

Fig. 4 is a fragmentary end view in perspective showing the manner of bending the end binders for attachment to the body of the box;

30 Fig. 5 is a view of the blank from which the metal binding strip is formed;

Figs. 6 and 7 are details.

A and B represent the wooden top and bottom respectively of an orange-box. A 35 binding strip 1 of iron, and substantially in the proportions shown in Fig. 5 is bent double, and has the diamond-shaped spurs 2 cut and struck therefrom from opposite sides and punched or driven into the wood 40 after the binding strip is in place, as clearly shown in Fig. 6. Holes 3 are also punched to receive nails, if desired.

The ends 4 of the binding strip protrude 45 and are adapted to be bent downwardly or upwardly, as the case may be, as shown in Fig. 4, and are provided with holes 5 to receive nails, whereby they are fastened to the sides of the box.

In this way, a simple, cheap, and effective 50 device is provided for practically making an iron-bound box which will withstand severe usage, and yet be economical in construction.

The diamond-points secure the iron binding strip rigidly to the edges of the wood,

and with their points extending outwardly as illustrated, it precludes the binding strip being pulled off, they extending only part way through the wood.

In applying the binding strip, it is first 60 folded around the edge, preferably by machinery designed for that purpose, and then the diamond points are punched or cut and driven deeply into the wood, with the points extending outwardly. 65

The protruding ends 4 of the binding strips may be of various lengths, for instance they might be made to meet half-way, thus forming a complete iron-bound box when the top and bottom are secured to 70 the body of the box.

I claim:

1. The combination with a member adapted to serve as a box cover or bottom, a substantially U-shaped metal binding strip encircling the end edge of the member, the ends of the strip projecting beyond the sides of the member and having outwardly pointed spurs pushed inwardly therefrom into the body of the said member. 75

2. The combination with a member adapted to serve as a box cover or bottom, a substantially U-shaped metal binding strip encircling the end edge of the member, the ends of the strip projecting beyond the sides of the member and having staggered outwardly-pointed spurs pushed inwardly therefrom into the body of the said member. 80

3. The combination with a member adapted to serve as a box cover or bottom, a substantially U-shaped metal binding strip encircling the end edge of the member, the ends of the strip projecting beyond the sides of the member, and having outwardly pointed spurs pushed inwardly from either side of 90 said U-shaped metal binding strip into the body of the said member, said spurs staggered both longitudinally and transversely of said strip. 95

4. In a box, the combination with a member adapted to serve as a box cover or bottom, with a substantially U-shaped metal binding strip encircling the end edge of the member, the ends of the strip projecting beyond the sides of the box, and having outwardly pointed spurs pushed inwardly therefrom into the body of the said member. 100

In testimony whereof I hereunto affix my signature.

SHELTON J. GUNN.
